UNITED STATES PATENT OFFICE.

HORACE M. HUFFMAN, OF DAYTON, OHIO, ASSIGNOR TO THE HUFFMAN MANUFACTURING COMPANY, OF DAYTON, OHIO, A CORPORATION OF OHIO.

DESIGN FOR A VALVE WHEEL.

Application filed March 10, 1927. Serial No. 21,076. Term of patent 14 years.

To all whom it may concern:

Be it known that I, HORACE M. HUFFMAN, a citizen of the United States, residing at Dayton, county of Montgomery and State of Ohio, have invented a new, original, and ornamental Design for Valve Wheels, of which the following is a specification, reference being had to the accompanying drawing forming a part thereof.

In said drawings Fig. 1 is a front elevation of a valve wheel showing my new design; Fig. 2 is an edge view of the same; and Fig. 3 is a transverse sectional view showing the shape of the radial ribs and cavities.

I claim:

The ornamental design for a valve wheel as shown.

HORACE M. HUFFMAN.
